INTAKE SILENCER

Benjamin Gratz Brown, Flint, Mich., assignor to
General Motors Corporation, Detroit, Mich., a
corporation of Delaware

Application November 4, 1935, Serial No. 48,128

3 Claims. (Cl. 181—59)

This invention relates to silencers of the resonator type in which the main duct consists of two telescopically related, radially spaced tubular members through whose interspace a chamber or a series of chambers which surround the duct are connected to it.

The invention resides in a modification of the passage which connects the duct with the chamber or series of chambers which makes it possible 10 to reduce the length of the silencer without unfavorably affecting its silencing characteristics.

For a better understanding of the nature and objects of this invention, reference is made to the following specification wherein there are described the embodiments of the invention which are illustrated in the accompanying drawings.

In the accompanying drawings:

Figure 1 shows, partly in elevation and partly in section, an air cleaner and silencer assembly 20 in whose silencer element there is incorporated one embodiment of this invention.

Figure 2 is a section taken on the line 2—2 of Figure 1 with parts broken away and in section.

Figure 3 shows, partly in elevation and partly in section, an air cleaner and silencer assembly 25 in whose silencer element there is incorporated another embodiment of this invention.

Figure 4 is a section taken on the line 4—4 of Figure 3.

The silencer element of the assembly shown in Figures 1 and 2 includes a cylindrical wall 10 and upper and lower end walls 11 and 12 which are suitably connected to the wall 10. Through the 35 center of the cylindrical element formed by the walls 10, 11 and 12, there extends a duct which consists of telescopically related tubes 14 and 15. The tube 14 extends through an opening in and is secured to the lower wall 12 and its upper end 40 terminates short of, but near the upper wall 11. The tube 15 extends through an opening in and is secured to the upper wall 11. It is coaxial with and of smaller diameter than the tube 14 and projects into the latter to about the level of the lower wall 12. The compartment defined by the 45 duct 14—15 and the walls 10, 11 and 12 is divided into two chambers 17 and 18 by a partition 19 through which extends a tube 20.

The cleaner element of the assembly forms no 50 part of this invention and it is, consequently, unnecessary to describe it in detail. Briefly, it consists of a cup-like member 21 with a stepped bottom which when in operation is filled with oil to about the level indicated by the reference character O. A tube 22 extends through a central

opening in and is secured to the bottom of the cup 21. The tube 22 supports a filter element which consists of an annular receptacle 23 which is somewhat smaller in diameter than the cup-like member 21 and whose outer wall extends upwardly beyond the side wall of the member 21 and defines with it an air intake opening 27. The receptacle 23 has openings 24 and 25 in its upper and lower walls and is filled with a suitable filtering medium 26. The outer wall of the filter element supports a cover 28 which closes the upper ends of the filter element and the tube 22 but is shaped so that air can flow from the upper end of the filter element into the tube.

Because the bottom of the cleaner element is stepped, to form a compact assembly of the cleaner and silencer elements, the top of the silencer element is made concave. Because the top of the silencer element is concave, the duct 14—15 of the silencer element is shorter than it would be if the top were approximately flat, as it has been in previous designs. Shortening the duct 14—15 naturally reduces the extent to which the tubes 14 and 15 overlap and, therefore, increases the acoustical conductivity of the annular passage 13 which connects the duct with the chamber 17 beyond that which it would be if the top 11 were flat. To compensate for this, there is secured to the upper wall 11 of the silencer element a ring-like member 29 which surrounds 30 and is radially spaced from the upper end of the tube 14. The provision of the member 29, in effect, increases the length of the annular passage 13 and permits the acoustical conductivity 25 of the passage to be reduced to the desired value 35 and, consequently, the operation of the silencer to be improved.

The cleaner and silencer elements are assembled as shown in the drawing with the lower end 40 of the cleaner element interfitting with the upper end of the silencer element and supported therefrom through a gasket 30. The cover 28 is secured to the cleaner element and the cleaner element is secured to the silencer element by a yoke 31 and a thumb screw 32.

The cleaner element of the assembly shown in Figures 3 and 4 differs materially from that shown in Figures 1 and 2 only in the inclusion of the perforated baffle 33. The silencer element of the assembly shown in Figures 3 and 4 differs 50 materially from that shown in Figures 1 and 2 only in the provision of a ring-like element 34 which is secured to the partition 19 around and in spaced relation to the lower end of the ring-like member 29. The provision of the member 34 in

effect still further increases the length and reduces the acoustical conductivity of the passage 13 and permits the length of the silencer element to be further reduced without unfavorably affecting its

5 silencing characteristics. It will, of course, be understood that additional elements, such as 29 and 34 which in effect would further lengthen the passage 13, provide additional turns therein and decrease its acoustical conductivity, may be employed if they are found desirable.

10 The cleaner and silencer assemblies shown in the drawing were designed for use in connection with the carburetor of an internal combustion engine to clean the air entering it and eliminate 15 the noises ordinarily emitted from it. These assemblies are designed to be installed on a carburetor by connecting the tube 14 to the air intake pipe of the carburetor.

15 When one of these assemblies is installed as indicated, and the engine on which it is installed is operating, air is drawn into the opening 27 and follows the path indicated by the arrows into the tube 22. During its passage from the opening 27 to the tube 22, the air is freed of foreign matter. 20 From the tube 22, the air is drawn through the duct 14-15 to the carburetor.

25 The silencer element is, of course, so tuned—that is the acoustical conductivity of the passages which connect the duct 14-15 with the chamber 30 17 and interconnect the chambers 17 and 18 and the volumes of the chambers 17 and 18 are so adjusted—in the manner described in the Wilson application Serial No. 470,700, filed July 25, 1930, that it will prevent noises emitted by the carburetor from reaching the atmosphere. It will, I think, be understood from what I have said that this invention facilitates the proper tuning of resonator silencers of the type under consideration.

35 40 I claim:

1. In a silencer, a duct through which sound waves may travel, the duct including two telescopically related, radially spaced tubular elements, a wall which encircles and is radially spaced from the duct, walls which with the tubular elements and the first-specified wall define a compartment which communicates with the duct through the aperture between the tubular elements, and an annular element which is connected to the same of the second-specified walls as the inner of the tubular elements and encircles and is radially spaced from the inner end of the

outer of the tubular elements so that it defines therewith an angularly disposed extension of the aperture through which the compartment communicates with the duct.

2. In a silencer, a duct through which sound waves may travel, the duct including two telescopically related, radially spaced tubular elements, a resonator which is arranged as a branch of the duct, the resonator including a wall which encircles and is radially spaced from the duct, and 10 walls which with the tubular elements and the first-specified wall define a compartment which communicates with the duct through the aperture between the tubular elements, and annular elements which are connected, respectively, to the 15 same of the second-specified walls as the inner of the tubular elements and encircles and is radially spaced from the inner end of the outer of the tubular elements and to the other of the second-specified walls and encircles and is radially spaced 20 from the inner end of the other of the mentioned annular elements so that they define with the outer of the tubular elements and each other angularly disposed extensions of the aperture through which the compartment communicates 25 with the duct.

3. In a silencer, a duct in which there are included two telescopically related, radially spaced tubular elements through which sound waves may travel, a resonator which is arranged as a branch 30 of the duct and includes a wall which encircles and is radially spaced from the duct and walls which with the tubular elements and the first-specified wall define a compartment which communicates with the duct through the aperture between the tubular elements, a wall which subdivides the compartment lengthwise into two chambers, an aperture through which the chambers communicate with each other, and annular 35 elements which are connected, respectively, to the same of the second-specified walls as the inner of the tubular elements and encircles and is radially spaced from the inner end of the outer of the tubular elements and to the third-specified wall 40 and encircles and is radially spaced from the inner end of the other of the annular elements so that they define with the outer of the tubular elements and each other angularly disposed extensions of the aperture through which the compartment 45 communicates with the duct. 50

BENJAMIN GRATZ BROWN.
